6 Claims. (Cl. 260—116)

The present invention relates to improvements in the recovery of organic acids from products of the destructive oxidation of liquid and solid, non-aromatic hydrocarbons.

5 It is already known that the destructive oxidation of non-aromatic hydrocarbons, such as mineral oil, paraffin wax, paraffin oil or oils containing the same, with the aid of oxygen, air or other oxygen bearing oxidizing agents at temperatures 10 between about 130° and 180° C. results not only in acid products containing oxygen, as for example carboxylic acids and hydroxy-carboxylic acids, but also greater or less amounts of neutral compounds containing oxygen, such as alcohols, 15 aldehydes, ketones, esters, lactones, estolides, lactides, aldehyde-alcohols and ketone-alcohols. In order to recover the valuable acid constituents, especially those which are present in the combined or modified form, namely esters and estolides, 20 it has been necessary hitherto to saponify the oxidation product with caustic alkalies or oxides or hydroxides of the alkaline earth metals.

We have now found that the organic acids, especially those present in the combined or modified form as esters, estolides, lactones and lactides, are recovered in an advantageous manner from products of the destructive oxidation of liquid to solid non-aromatic hydrocarbons by treating the oxidation products in a closed vessel and at 30 a temperature, which is at least 75° C. but is always kept below the boiling temperature of water at the pressure employed, which is produced both by heating and by the evolution of carbon dioxide, with an aqueous solution of an 35 amount of alkali metal carbonate, as for example sodium, potassium or ammonium carbonate, at least corresponding to the saponification value of the oxidation product, preferably in excess thereof, the resulting alkali metal salts being worked 40 up into free fatty acids by acidification after the removal of the unsaponifiable constituents. Contrary to expectation, not only the free carboxylic acids but also those which are present in the oxidation products in a combined form, such as 45 waxes, lactones, esters, estolides and lactides, are almost completely converted into alkali metal salts.

We have already proposed together with others to remove the acids present in the said products 50 by a treatment with solutions of alkali metal carbonates, but the acid constituents present in the combined form have not hitherto been split off and recovered. We have found that this complete saponification can be attained only by the before- 55 mentioned complete saponification at elevated

temperature, especially those above 100° C., with the simultaneous employment of elevated pressure. When working in this manner more carboxylic acids are obtained from the reaction mixture when working up the reaction mixture than corresponds to the acid value of the oxidation product employed.

The amount of alkali metal carbonate (which term is intended to include ammonium carbonate) is preferably calculated on the saponification value of the oxidation product, which is usually considerably greater than, as for example twice as great as, the acid value. It is, however, advantageous to use an amount of alkali carbonate slightly in excess, as for example from 60 about 5 to about 10 per cent in excess, of the amount so calculated for complete saponification. Still higher quantities may be employed but an excess of more than 10 per cent is superfluous 65 and unduly expensive. The alkali carbonate can be employed in the form of from 5 per cent aqueous solutions to hot saturated solutions and is preferably employed in the form of an about 70 20 per cent aqueous solution, the product to be saponified being slowly introduced into the hot 75 solution of carbonate. At the commencement of the treatment the temperature is kept usually between 60° and 100° C., preferably between about 80° and about 95° C., until the greater part of the carbon dioxide formed by the conversion of the free carboxylic acids present has been evolved. Towards the end of the reaction, the temperature is preferably raised above 100° C. up to say 85 350° C., generally, however, to from about 160° to about 185° C., and the pressure increased 90 above 1 atmosphere, usually from 8 to 9 atmospheres, or even to 15 or more atmospheres. Care should be taken for a uniform removal of the 95 carbon dioxide evolved. It is of special advantage thoroughly to mix the reaction mass during the treatment, as for example by means of a high-speed stirrer. For example, the saponification may be carried out in a turbo-mixer or vessel provided with turbo-stirrers, in which process the 100 time required for saponification is very short. By suitable arrangement of the inlet and outlet devices and by continuous withdrawal of the saponified product while introducing fresh initial material, the saponification in the turbo-mixer may readily be rendered continuous. Processes for carrying out the saponification are further illustrated by the diagrams in Figures 1 and 2 annexed hereto, Figure 1 showing continuous working in a direct flow and Figure 2 showing a

modification of this process in which the final saponification may be carried out in a cycle.

When the saponification is completed the unsaponifiable constituents separate out from the 5 soap solution, if necessary after diluting the reaction product with water, when a concentrated carbonate solution has been used for the reaction, as the upper layer which is removed. Any remaining unsaponifiable constituents in the solution 10 may be completely removed by extraction with organic solvents, as for example gasoline, carbon tetrachloride, other chlorinated hydrocarbons and ethyl ether. If desired, the unsaponifiable constituents may be subjected to 15 oxidation again, if necessary after washing for a short time with dilute alkali carbonate solution or water in order to remove small quantities of soap contained therein.

The following examples will further illustrate 20 the nature of this invention, but the invention is not restricted to these examples.

Example 1

100 kilograms of a crude oxidation product 25 having an acid value of 100 and a saponification value of 150, obtainable by the destructive oxidation of hard paraffin wax by blowing it for several hours with air at about 150° C. in the presence of 0.1 per cent by weight of the wax of 30 sodium carbonate in the form of a concentrated aqueous solution, is allowed to flow in a thin stream at 80° C. into a solution of 15.6 kilograms of anhydrous sodium carbonate in 70 kilograms of water while stirring vigorously under atmospheric pressure. After the initial turbulent evolution of carbon dioxide has ceased, the mixture is transferred to a stirring autoclave and further treated for about an hour at 120° C., whereby the carbon dioxide set free is removed by frequently 40 releasing the pressure in the autoclave down to 3 atmospheres. The soap solution obtained is diluted with water and extracted with benzine. Then by acidification with sulphuric acid about 50 kilograms of pure fatty acids are obtained.

45 *Example 2*

100 kilograms of an oxidation product having 50 an acid value of 75 and a saponification value of 140 and obtained from soft paraffin wax by blowing it for several hours with air at about 150° C. are stirred together with a solution of 14.3 kilograms of anhydrous sodium carbonate in 60 kilograms of water at about 90° C. under atmospheric pressure. After the initial turbulent evolution of carbon dioxide has ceased, the mixture is charged several times at 170° C. through a 55 turbomixer (3000 revolutions per minute) provided with a circulating vessel, whereby a pressure of about 9 atmospheres is maintained. After 60 a few minutes the saponification is almost completely effected and the treatment is terminated after about 15 minutes. The reaction mixture is worked up into free fatty acids in the manner described in Example 1.

65 What we claim is:—

1. In the separation of organic acids from products of the destructive oxidation of from liquid to solid, non-aromatic hydrocarbons, the step which comprises heating such oxidation 70 product in a closed, pressure-tight vessel to a temperature between 75° C. and the boiling point of water at the pressure employed together with

an at least 5 per cent aqueous solution of a quantity of an alkali metal carbonate at least corresponding to the saponification value of said oxidation product.

2. In the separation of organic acids from 80 products of the destructive oxidation of from liquid to solid, non-aromatic hydrocarbons, the step which comprises heating such oxidation product in an open vessel together with an at least 5 per cent aqueous solution of a quantity of an alkali metal carbonate at least corresponding to the saponification value of said oxidation product, to a temperature below the boiling point of water until the evolution of carbon dioxide has ceased and then heating the whole in a closed 85 pressure-tight vessel to a temperature between 75° C. and the boiling point of water at the pressure employed.

3. In the separation of organic acids from 90 products of the destructive oxidation of from liquid to solid, non-aromatic hydrocarbons, the step which comprises heating such oxidation product in an open vessel together with an at least 5 per cent aqueous solution of a quantity of an alkali metal carbonate at least corresponding to the saponification value of said oxidation product, to a temperature below the boiling point of water until the evolution of carbon dioxide has ceased and then heating the whole in a closed 95 pressure-tight turbomixer to a temperature between 100° C. and the boiling point of water at the pressure employed.

4. In the separation of organic acids from 100 products of the destructive oxidation of paraffin wax, the step which comprises heating such oxidation product in an open vessel to a temperature between 60° and 95° C. with an at least 5 per cent aqueous solution of a quantity of an alkali metal carbonate at least corresponding to the saponification value of said oxidation product 105 until the evolution of carbon dioxide has ceased and then heating the whole in a closed, pressure-tight vessel to a temperature between 100° and the about 185° C.

5. In the separation of organic acids from 110 products of the destructive oxidation of paraffin wax, the step which comprises heating such oxidation product in an open vessel to a temperature between about 60° and about 95° C. with an aqueous solution of a quantity of sodium 115 carbonate, exceeding that theoretically required for complete saponification by from about 5 to about 10 per cent, until the evolution of carbon dioxide has ceased and then heating the whole in a closed, pressure-tight vessel to a temperature between 100° and about 185° C.

6. In the separation of organic acids from 120 products of the destructive oxidation of paraffin wax, the step which comprises heating such oxidation product in an open vessel to a temperature between about 60° and about 95° C. with a quantity of an about 20 per cent aqueous solution of sodium carbonate, exceeding that theoretically required for complete saponification by from about 5 to about 10 per cent, until the 125 evolution of carbon dioxide has ceased, and then heating the whole in a closed, pressure-tight vessel to a temperature between 100° and about 185° C.
